AUTOMATIC FIREARM

Joseph C. Cantley, Beverly, and Arthur F. Pym, deceased, late of Topsfield, Mass., by George H. Heys, administrator, Swampscott, Mass., assignors to United Shoe Machinery Corporation, Flemington, N. J., a corporation of New Jersey

Application May 14, 1945, Serial No. 593,640

8 Claims. (Cl. 89—3)

1

This invention relates to firearms and more particularly to mechanism for insuring an approximately constant rate of fire in automatic guns.

It has been found that the rate of fire of guns installed in airplanes, for example, is dependent to a considerable extent upon the wind pressures and temperatures to which the guns are subjected, the greater the wind pressure and/or the lower the temperature, the slower the cyclic rate of fire of the guns. It is desirable at all times to maintain as nearly as practicable the normal firing rate of the gun, having in consideration, for example, the need for maximum fire power and the most efficient operation of mechanism which automatically feeds ammunition to the gun.

It is an object of the present invention to provide a simple, effective device for maintaining a sustained firing rate in automatic guns operating under adverse conditions. With the above object in view and in accordance with a feature of the present invention, there is provided, in an automatic gun, a power-driven member having a substantially uniform velocity-curve, a member operative in response to recoil and counter-recoil movement of parts of the gun, a resistor unit, comprising fluid and a housing therefor, for opposing the recoil and counter-recoil movement of said parts of the gun, a valve for controlling flow of fluid in said housing, and mechanism responsive to differences in speed between the power-driven and the gun-operated members for controlling said valve to cause the velocity-curve of the gun-operated member to approximate the velocity-curve of the power-driven member.

The power-driven member and the gun-operated member, which is operatively connected to the tube or barrel of the gun, have the form of racks which reciprocate in directions opposite to each other along spaced parallel guideways respectively, the teeth of one of the racks being spaced from and in opposed relation to the teeth of the other rack. Opposing the recoil and counter-recoil movement of the tube and other parts of the gun is said resistor unit, the resistance of which varies in accordance with the setting of said valve. In meshing relation with the teeth of the racks is a pinion rotatably mounted upon a slide which is movable in a guideway arranged parallel to the guideways of the above-mentioned racks and is operatively connected to the valve. The velocity-curve of the tube-operated rack, when the gun is being

fired at its normal rate, serves as a basis for computing the velocity-curve of the power-driven rack.

When the power-driven and the tube-operated racks are reciprocated at the same speed in opposite directions along their respective guideways, the pinion, which is rotatably mounted upon the valve operating slide, rotates but does not cause the slide to move along its guideway. When, however, the tube-operated rack is moved slower than the power-driven rack, the slide is moved along its guideway by the pinion, causing the valve to reduce the opposing effect of the resistor unit, thereby enabling the tube to accelerate to its normal speed for its particular displacement from battery position. When the tube speeds up sufficiently to cause the tube-operated rack to move faster than the power-driven rack, the pinion carrying slide is moved in an opposite direction along its guideway, causing the valve partially to close, with the result that the opposing effect of the resistor unit is increased to such an extent that the tube slows down approximately to its normal speed for that particular displacement from battery position. The valve is so operated that the speed of the tube-operated rack will at any particular moment be substantially equal to the speed of the power-driven rack, thereby insuring that the cyclic rate of the gun shall be approximately constant irrespective of the conditions under which it is operated.

The various features of the invention will be understood and appreciated from the following detailed description read in connection with the accompanying drawings, in which

Fig. 1 is a side view, partly broken away and partly in section on line I—I of Fig. 3, showing the illustrated device incorporated in a 37 mm. gun of the general type disclosed in United States Letters Patent No. 1,525,065, granted February 3, 1925, on an application filed in the name of John M. Browning.

Fig. 2 is a side view similar to Fig. 1, partly in section on line II—II of Fig. 3;

Figs. 3 and 4 are sections on lines III—III, IV—IV of Figs. 2 and 1, respectively;

Figs. 5 and 6 are sections on lines V—V and VI—VI, respectively, of Fig. 4; and

Fig. 7 is a time-displacement chart of recoiling parts of the gun.

The illustrative 37 mm. gun comprises a barrel or tube 20 (Figs. 1, 2 and 3) an enlarged breech portion of which is slidably mounted for recoil and counter-recoil movement in a cylindrical

bore 22 (Figs. 2 and 3) of a trunnion block 24, the tube being further supported for sliding movement in said bore by a brass bushing 26 (Figs. 1 and 2) secured to the forward end of the trunnion block. Secured by screws 28 to the trunnion block 24 are trunnions 30 which are swiveled upon a cradle (not shown) suitably mounted for rotation about a vertical axis for moving the gun in azimuth. Since the 37 mm. gun illustrated herein is of the type used extensively in this and other countries and is well known to those skilled in the ordnance art, only such parts of the gun as are necessary in disclosing the illustrative device need be described herein.

The tube 20, together with a tube extension 32 (Fig. 2) threaded onto the rear end of the tube, is moved rearward approximately 9½ inches during recoil along the bore 22 of the trunnion block 24 from its battery position, shown in full lines Fig. 2, the tube and its extension being returned to battery position from its fully recoiled position, shown in dash lines, by a recuperator or resistor unit 34. Formed integral with and extending downward from the trunnion block 24 is a support 36 in a bore of which is secured a two-part recuperator housing 38 containing oil. Secured to the housing 38 is a bushing 40 (Figs. 1, 4 and 5) provided with three circumferentially spaced elongated oil by-pass openings 42 (Figs. 1 and 4), the purpose of which will be explained later. Slidably mounted in the bushing 40 is a piston 44 (Figs. 1 and 5) threaded onto the forward end of a rod 46 which passes through registering openings 48, 50 (Fig. 2) formed respectively in a rear closure cap 52 threaded into the recuperator housing 38 and in a depending portion of the tube extension 32. The rod 46 is secured to the tube extension 32 by a nut 54 which is threaded onto the rear end of the rod, fits in a hole in the tube extension, and is turned to draw a collar 56 of the rod into clamped engagement with said extension.

The forward end of the recuperator housing 38 is closed by a cap 58 (Figs. 1 and 5) threaded into the housing. Surrounding the rod 46 and interposed between the piston 44 and the rear closure cap 52 is a spring 60 which is compressed during the recoil movement of the tube 20 and the tube extension 32 and serves to move said tube, together with its extension, back to battery position. The piston 44 is moved lengthwise of the housing 38 from its full-line position (Fig. 1) to its dash-line position and back again, oil being transferred from one of the chambers 62 (Figs. 1, 2 and 5), 64 (Figs. 1 and 5) at the rear and front, respectively, of the piston, to the other through the by-pass openings 42 (Figs. 1 and 4) in the bushing 40. The rear closure cap 52 (Fig. 2) of the recuperator housing 38 is provided with a suitable stuffing box 66 to insure against oil seeping from the rear chamber 62 between the cap and the piston rod 46.

It will be noted (Fig. 1) that the oil by-pass openings 42 extend well forward of a front working face 68 of the piston 44 in its full-line battery position and rearward approximately to a rear working face 70 of the piston in its recoiled dash-line position. The bushing openings 42, which are considerably smaller in cross section than are corresponding openings in the bushing of the 37 mm. gun now in common use, serve to by-pass oil around the piston 44, the oil in the rear chamber 62 of the recuperator

housing 38, together with the recuperator spring 60, opposing recoil movement of the tube 20, and the oil in the front chamber 64 of the housing opposing the counter-recoil movement of the tube, which recoil movement is effected by the action of the recuperator spring.

It is desirable that the gun shall fire at its normal cyclic rate (approximately 150 shots per minute) even under adverse conditions, such, for example, as high wind load and extremely low temperatures. Moreover, it is further desirable that when the gun has an automatic ammunition feed, such, for example, as disclosed in an application for Letters Patent of the United States Serial No. 637,236, filed December 26, 1945, in the names of Ernest W. Stacey and Frank W. Reinhold, the regular firing rate shall be substantially maintained in order that the mechanism which feeds the shells to and chambers said shells in the gun shall operate most effectively.

When the gun is being fired under ordinary conditions at its normal cyclic rate, the velocity-curves of the tube 20 and the tube extension 32 on the one hand and a lock frame (not shown) on the other hand are approximately uniform or constant, such curves being readily computed from the 37 mm. gun time-displacement chart such as illustrated in Fig. 7.

As will appear later, when the illustrative gun fires at a subnormal rate because of adverse conditions, resistance operating against recoiling and counter-recoiling movement of the tube 20, together with its extension, is automatically decreased in accordance with the reduction in speed of said parts, with the result that said parts of the gun almost immediately acquire a speed slightly greater than the normal speed of such parts for that particular portion of their cycle. When this occurs, the resistance operating against the recoiling and counter-recoiling parts of the gun immediately increases and accordingly the speed of such parts is reduced slightly below their normal speed for that particular portion of the cycle. When operating under constantly changing wind and temperature conditions, the resistance operating against the recoiling and counter-recoiling parts of the gun is continuously varied through the provision of mechanism which is hereinafter described and is constructed and arranged to insure that the velocity-curves of said parts of the gun remain approximately uniform and are approximately the same as the velocity-curves of said parts when the gun is operating under normal conditions. With such a control, it will be apparent that the gun maintains a substantially constant cyclic rate regardless of the conditions under which it is fired.

With a view to varying the resistance operating against the recoiling and counter-recoiling parts of the gun, there is provided a block 72 (Figs. 1, 4, 5 and 6) having a pair of oil passages 74 (Figs. 4 and 5), 76 (Figs. 1 and 6) the rear ends of which are in registration with openings 78 (Fig. 5), 80 (Fig. 1), respectively, in the recuperator housing 38 and afford access to the rear oil chamber 62. The forward ends of the passages 74, 76 are in registration with aligned openings 82 (Fig. 5), 84 (Fig. 1), respectively, which are formed in the recuperator housing 38 and the bushing 40 and afford access to the front oil chamber 64. The block 72 is held in forced engagement with the bottom of the recuperator housing 38 by a cylindrical portion 86 (Figs. 1 and 4) of the block

which fits on and is secured to the housing. As above stated, the passages 74, 76, which may be said to include the openings 78, 80 and the openings 82, 84, respectively, extend forward to positions just in advance of the piston 44 in its full-line battery position (Fig. 1) and rearward to positions just behind the piston in its recoiled position (shown in dash lines, Fig. 1). Mounted in the passages 74, 76 are check valves 88, 90, respectively, the valve 90 preventing flow of oil in the passage 76 from the rear oil chamber 62 to the front oil chamber 64 of the recuperator housing 38 and the valve 88 preventing flow of oil in the passage 74 from the front to the rear oil chamber.

Mounted for rotation in the block 72 is a valve 92 (Figs. 4, 5 and 6) having ports 94, 96 which may be moved into registration with the passages 74, 76, respectively. In order to vary the flow of oil in directions 95 (Fig. 5), 97 (Fig. 6) through the passages 74, 76, respectively, for the purpose of controlling the cyclic rate of the gun firing under adverse conditions, the valve 92 is actuated through mechanism which will now be described. When the valve 92 is in the position shown in Figs. 5 and 6, its ports 94, 96 are so positioned that they restrict to a considerable extent the flow of oil through the passages 74, 76, the combined flow of oil through said ports thus positioned and through the openings 42 in the recuperator bushing 40 restricting the flow of oil from one chamber 62, 64 to the other approximately to the same extent that oil is restricted in larger but corresponding recuperator bushing openings alone of the 37 mm. gun now in use. Accordingly, when the gun is operating under normal conditions, the valve 92 is positioned approximately as illustrated in Figs. 5 and 6, the flow of oil in the passages 74, 76 being somewhat restricted. Since the unitary valve 92 comprises ports 94, 96 for regulating the flow of oil through the passages 74, 76, respectively, such valve may be considered as constituting a pair of valves and be referred to as such.

In order that the velocity-curve of the tube 20, and accordingly the recoil portion of the velocity-curve of the lock frame of the gun, shall be approximately uniform and similar to the velocity-curves of corresponding parts of the gun fired at a cyclic rate of 150 rounds per minute, the valve 92 is automatically rotated, if necessary. Such rotation of the valve is effected through mechanism which will be described presently and which operates during the recoil and counter-recoil movement of the parts of the gun in order to allow oil in greater or less quantities to flow through the passages 74, 76 in directions 95 (Fig. 5), 97 (Figs. 1 and 6), respectively, with the result that the resistance opposing the recoil and counter-recoil movement of the tube is varied in accordance with changes in the setting of the valve.

Mounted for rotation at a constant predetermined speed in a bracket 98 (Fig. 3) secured to the trunnion block 24 is a shaft 100 which is operatively connected through a suitable clutch 102 to a shaft 104 also rotatably mounted in the bracket. Secured to the shaft 104 is a cam 106 (Figs. 1 and 3) having a camway 108 (Fig. 1) in which fits a follower 110 rotatably mounted upon a lever 112 (Figs. 1, 2 and 3). The lever 112 is swiveled at its upper end upon a fulcrum pin 114 secured to the trunnion block 24 and has at its lower end an elongated slot 116 (Fig. 1) for receiving a pin 118 secured to the rear end of a

rack 120 (Figs. 1 and 3) mounted for forward and rearward reciprocation in a guideway 122 of a depending portion 124 of the trunnion block 24.

It will be noted upon examining the time displacement chart shown in Fig. 7 that the tube 20 and the tube extension 32 of the above-identified 37 mm. gun arrive at a battery position and remain there at rest for a short period, represented by reference numeral 126, while the lock frame (not shown) of the gun moves forward under spring action to its battery position, the shell during such rest period being chambered and the breech block (not shown) being locked in its battery position. Accordingly, the camway 108 is designed to cause the lever 112 to remain at rest during the rest period of the tube 20, the follower 110 at such time being in engagement with a concentric portion 128 (Fig. 1) of the camway.

20 Slidably mounted in a rectilinear guideway 130 (Figs. 2 and 3) of the depending portion 124 of the trunnion block 24 is a rack 132 the rear end of which has secured to it a lug 134 (Figs. 1 and 2) provided with a transverse slot 136 (Fig. 2) in which fits a depending flange 138 of the tube extension 32. Rotatably mounted in the depending portion 124 of the trunnion block 24 is a shaft 140 (Figs. 1, 2 and 3) to which are secured large and small pinions 142 (Figs. 2 and 3), 144 (Figs. 1 and 3), respectively, the pinion 142 being operatively connected to the rack 132 and the pinion 144 being operatively connected to a rack 146 slidably mounted in a rectilinear guideway 148 which is formed in said depending portion 124. The pinion 142 has a diameter approximately three times that of the pinion 144 and accordingly the travel of the rack in its guideway 148 is one-third of the recoil and counter-recoil travel of the tube 20 and is also in a reverse direction to the direction of travel of said tube.

25 Slidably mounted in aligned guideways 150, 152 (Fig. 1) of the block 72 and the depending portion 124 of the trunnion block 24 is a rack or rack slide 154 (Figs. 1 and 4) upon the rear bifurcated end of which freely rotates a pinion 156 (Fig. 1) constructed and arranged to mesh with teeth of racks 120, 146. The teeth of the rack slide 154 mesh with teeth of a pinion 158 secured to the rotary valve 92.

30 It will be apparent that when the racks 120, 146 move at the same speed in opposite directions along their parallel guideways 122, 148, the pinion 156 will rotate freely upon the rack slide 154 but will not impart to the slide 154 a translatory movement along its guideways 150, 152 which are parallel to the guideways 122, 148. Should the tube-operated rack 146 slow down and thus move slower than the rack 120, which may be referred to as a control or speed regulating rack, during the recoil movement of the tube 20, for example, the slide 154 will move to the left, as viewed in Fig. 1, causing the valve 92 to rotate clockwise, as viewed in Fig. 5, with the result that resistance to the flow of oil from chamber 62 to chamber 64 of the housing 38 is decreased. The effect of such action is to cause the recuperator piston 44 to offer less resistance to the recoil movement of the tube 20. When this occurs, the tube 20 immediately speeds up until it causes the rack 146 to move faster than the rack 120, with the result that the rack slide 154 moves to the right, as viewed in Fig. 5, causing the valve 92 to be rotated counterclockwise and thereby restricting the flow of oil in the direction

95 in the passage 74 and causing the recuperator piston 44 to offer increased resistance to the recoil movement of the tube 20.

If, during its counter-recoil movement, the tube 20 fails to maintain its desired velocity-curve, the rack 146 slows down with relation to the rack 120, causing the rack slide 154 to move to the right, as viewed in Fig. 1. Such action causes the valve 92 to move counterclockwise, as viewed in Fig. 6, and accordingly to offer less resistance than previously to the flow of oil in direction 97 through the passage 76. As the resistance to counter-recoil movement of the tube 20 is reduced the tube 20 speeds up and attains a velocity sufficient to cause the rack 146 to move faster than the rack 120 and thus to move the rack slide 154 to the left, as viewed in Fig. 1, with the result that the valve 92 is rotated clockwise, as viewed in Fig. 6, and offers increased resistance to the flow of oil through the passage 76. When this occurs the recuperator piston 44 offers increased resistance to the tube 20 which tends to slow down to its normal speed for its particular displacement from battery position.

The construction of the above-described operating parts is such that the device is sensitive to slight variations in speed between the racks 120, 146 and responds rapidly to said variations, the valve 92 moving almost continuously back and forth to a slight extent when continuously varying operating conditions are encountered.

The shaft 100 is driven by a constant speed motor (not shown) for example. When the gun is being fired automatically, the clutch 102 is operative to couple the shafts 100, 104 so as to rotate the shaft 104 at a fixed speed, a solenoid 160 being continuously energized during such time to hold the clutch in its driving position, shown in Fig. 1.

When single shots are being fired by the gun, it is desirable that the rack 120 shall be set in motion upon pulling the trigger (not shown) and that upon completion of the cycle of the gun the rack shall come to rest. The illustrative control is such that when the trigger is pulled a circuit is closed, causing the solenoid 160 to become energized and thus to throw in the clutch 102, thereby rotating the cam 106 at a constant speed. Upon release of the trigger the above-mentioned circuit is opened, but a relay is provided to keep the solenoid energized until a switch 162 (Fig. 1) is engaged by a projection 164 on the cam 106, at which time the solenoid is de-energized and the clutch 102 is thrown out, the shaft 104, through the provision of a multiple-plate brake (not shown) associated with the clutch, coming quickly to and remaining at rest until the gun is again fired.

Having described our invention, what we claim as new and desire to secure by Letters Patent of the United States is:

1. In an automatic gun, a unit for resisting recoil and counter-recoil movement of parts of the gun, means for varying the amount of resistance offered by said unit, a movable control member having a substantially uniform velocity-curve, a member movable in response to recoil and counter-recoil movement of one or more of said parts of the gun, and mechanism operative in response to differences in speed between said members for controlling said means.

2. In an automatic gun, a power-driven member having a substantially uniform velocity-curve, a member operative in response to recoil and counter-recoil movement of parts of the gun, a

resistor unit, comprising fluid and a housing therefor, for opposing the recoil and counter-recoil movement of said parts of the gun, a valve for controlling flow of fluid in said housing, and mechanism responsive to differences in speed between the power-driven and the gun-operated members for controlling said valve to cause the velocity-curve of the gun-operated member to approximate the velocity-curve of the power-driven member.

3. In an automatic gun, a member movable in response to recoil and counter-recoil movement of parts of the gun, a power-driven member having a substantially uniform velocity-curve, means for resisting recoil and counter-recoil movement of said parts of the gun, said means comprising fluid, a housing therefor, and a valve for restricting flow of fluid in the housing to control the rate of recoil and counter-recoil movement of said parts of the gun, and valve operating mechanism which is responsive to differences in speed between the gun-driven member and the power-driven member and which is constructed and arranged to operate the valve and to insure that the cyclic rate of the gun shall be approximately equal to that of the power-driven member.

4. In an automatic gun, a member movable in response to movement of recoiling and counter-recoiling parts of the gun, a control member, means for moving the control member in a substantially uniform velocity-curve, a valve, a fluid containing resistor unit for controlling the rate of recoil and counter-recoil movement of said parts of the gun and accordingly the cyclic rate of the gun in accordance with the setting of said valve, and means movable in response to differences in speed between said members for operating said valve.

5. In an automatic gun, a power-driven member having a substantially uniform velocity-curve, a member movable in response to recoil and counter-recoil movement of parts of the gun, a resistor unit for opposing the recoil and counter-recoil movement of said parts of the gun, mechanism for varying the amount of resistance with which said unit opposes the recoil and counter-recoil movement of the gun, and means responsive to differences in speed between the power-driven member and the recoil and counter-recoil driven member, said means being constructed and arranged so to control said mechanism that the velocity-curve of the recoil and counter-recoil driven member is approximately the same as the velocity-curve of the power-driven member.

6. In an automatic gun, a piston movable in opposite directions in response to recoil and counter-recoil movement of one or more parts of the gun, fluid housing means constructed and arranged to resist movement of said piston in opposite directions, a member responsive to movement of said one or more parts of the gun, a power-operated member having a velocity-curve which is approximately uniform, fluid flow control means for varying resistance operative against the piston during recoil and counter-recoil movement of the gun, and mechanism operative in response to differences in speed between said members for operating said flow control means whereby to vary resistance of fluid in said fluid housing means against said piston.

7. In an automatic gun, a barrel mounted for recoil and counter-recoil movement, a housing for fluid, a piston slidably in the housing in response to movement of said barrel, said piston having fluid engaging working faces, passages

connecting chambers of the housing which are located opposite the working faces respectively of the piston, valves arranged in the respective passages, a rack, power-driven means for reciprocating said rack in a substantially uniform velocity-curve, a rack movable in response to the recoil and counter-recoil movement of the barrel, a freely rotatable pinion which is operatively connected to both said racks and is also mounted for movement in a translatory path, said pinion being rotated but not moved in said translatory path when the barrel-operated rack moves at the same velocity as and in an opposite direction to the power-driven rack, said pinion being rotated and also moved in said translatory path when the velocity of the barrel-operated rack is different from that of the power-driven rack, and means responsive to translatory movement of the pinion for varying the setting of the valves.

8. In an automatic gun, a rack driven in a rectilinear path in response to recoil and counter-recoil movement of parts of the gun, a fluid containing resistor unit for opposing recoil and counter-recoil movement of the gun, valves for varying the resistance offered by said unit to the recoil and counter-recoil movement of said parts

of the gun, a control rack which is reciprocable in a rectilinear path parallel to the path of reciprocation of the gun-driven rack and which moves in a direction opposite to the direction of movement of the gun-driven rack, said control rack having a substantially uniform velocity-curve as it moves in said path, a slide, a pinion rotatably mounted upon the slide and positioned between and in meshing relation with the racks, said pinion being rotated but not operative to move said slide when the racks move at the same speed in opposite directions, said pinion being rotated and operative to move the slide when the gun-driven rack moves at a speed different from that of the control rack, and means operative in response to movement of the slide for causing said valves to open and close in order that the gun-driven rack shall have a velocity-curve approximately the same as that of the control rack, thereby insuring that the gun shall have a substantially constant cyclic rate.
